BAG

Mikael Vogel-Jorgensen, Frederiksberg, near Copenhagen, Denmark, assignor to F. L. Smidt & Co., New York, N. Y., a corporation of New Jersey

Application October 8, 1937, Serial No. 167,947
In Great Britain October 17, 1936

1 Claim. (Cl. 229—62.5)

This invention relates to block-bottom valve bags for containing pulverized or granular materials, and is concerned with bags which are closed by folding crossbottom parts one upon the other and securing the overlapped parts together in any suitable manner.

In the manufacture of bags of the type referred to, it is desirable, for reasons of economy, to use as small an amount of paper as possible, and, therefore, in folding the paper to form the bottom of the bag, the shortest possible length of the tubular part of the bag is employed. The strength of the bottom of the bag depends on the manner of securing together the folded side flaps, and if the overlap of the flaps is too narrow, the bottom closure will be weak and, in addition, the valve projecting into the bag will be so short as to be liable to be forced outward by the contents and thus permit leakage.

In order to increase the strength of the bottom of such a bag, and at the same time to increase the length of the valve, the use of a strip of paper affixed to the bottom so as to extend around the edge of the side flaps and into the valve has been suggested, but it has been found in practice that such a reinforcing strip frequently becomes cracked. This may be caused by the weight of the bag as the latter is supported on the filling spout or by the inside pressure exerted during the filling, and the result is that the valve is liable to be forced outward in subsequent handling.

In an attempt to strengthen the bottom and lengthen the valve of such a bag, the walls of the bag have been cut through so as to provide separate side and end flaps, and by this expedient, the side flaps may be made somewhat larger than would otherwise be the case. Such a procedure produces a longer valve and a larger overlap between the side flaps so as to permit them to be secured together more strongly, but it introduces weakness at other places. Thus, in a bag of such construction, the paper near the corners of the bottom is liable to burst, rendering the bag defective as well as injuring the valve.

The present invention is directed to the provision of a novel bag of the block-bottom type which overcomes the disadvantages of the prior bags above mentioned, and the new bag has additional advantages, which will be explained hereafter in detail.

According to the invention, the side flaps of the cross bottom of the bag are enlarged and separated from the corresponding end flaps by cuts

extending through one or more of the plies of the bag walls and lying parallel to the axis of the bag tube, when the flaps are in unfolded condition. The flaps are folded inwardly in the usual way to close the end of the bag and thereafter the corners of the bottom are provided with one or more reinforcing strips which may be affixed by adhesive. The width of these strips is greater than the distance by which the incisions or cuts are separated when the side flaps are folded one over the other, and the reinforcing means extend lengthwise of the bottom beyond the incisions. A strong bag structure is thus produced which is free of the weaknesses of the prior constructions.

For a better understanding of the invention, reference may be had to the accompanying drawings, in which

Figure 1 is a plan view of the bottom of a bag of the invention showing the parts at one stage in the folding;

Figure 2 is a view similar to Figure 1 showing the folding completed;

Figure 3 is a view similar to Figure 2 showing the bag after the application of the reinforcing means;

Figure 4 is a sectional view on the line 4—4 of Figure 3;

Figures 5 and 6 are sectional views similar to Figure 4 but of modified constructions;

Figure 7 is a view similar to Figure 3 of a modification; and

Figure 8 is a sectional view on the line 8—8 of Figure 7.

Referring to the drawing, the bag illustrated in Figure 1 has the usual tubular section 10, at the ends of which have been made cuts extending in a direction parallel to the axis of the bag tube prior to the commencement of the folding operations, each cut separating one of the side flaps 11a, 11b from one of the end flaps 12a, 12b. After inward folding of the end flaps in the usual manner along the lines 13, the cut edges 14 of the end flaps lie parallel to the greatest width of the bottom of the bag while the cut edges 15 of the side flaps lie at right angles thereto, as shown. The folding operations are completed by the inward folding of the side flaps 11a, 11b along the lines A, B lying on opposite sides of the long axis of the bottom, and at this stage, the bottom of the bag is in the condition illustrated in Figure 2. The overlap of the side flaps is such that the free edge 16a or 16b of each side flap lies beyond the cut edges 14 of the end flaps 15.

flaps at the opposite side of the long axis of the bottom.

The length of the valve is then represented by the distance between the aligned edges 15 of 5 the side flaps and the end edge 17 of an end flap, and at the end of the bottom opposite the valve, the portions of the end flap and side flaps lying in overlapping relation are secured together, as by an adhesive. With the bottom so formed, the 10 places of greatest weakness are at the points 18, 19 which are at the ends of the cuts, and to strengthen these points, a reinforcement is provided in the form of a strip 20. This strip is of paper affixed to the outer surface of the side flap 15 11a and is of such dimensions and is so placed that its inner end lies inward beyond the edge 17 of the end flap and its outer end lies outwardly beyond the edges 15 of the side flaps. Preferably, when the end and side flaps at the corner 20 opposite the valve corner are secured together by adhesive, a similar reinforcement 21 is used at that corner.

In the construction illustrated in Figure 5, the reinforcement employed at the valve end includes a strip 22 similar in dimensions and location to the strip 20 and a second reinforcing strip 23. The strip 23 is secured to the under surface of the upper valve flap, generally designated 24, and extends from a point inward from the inner 30 edge 17 of the lower valve flap out beyond the outer edge of the upper flap. The projecting ends of the reinforcing strips 22, 23 are then secured together, as shown. When the reinforcing strip 23 is employed, affixed to the under 35 surface of the under valve flap, the strip 22 may be omitted, if desired.

In the modified construction illustrated in Figure 6, the reinforcement consists of a single strip 25 which is affixed to the upper surface of the 40 upper valve flap, extends outwardly beyond the edge of the flap, and is then folded back upon itself along the line 26 and affixed to the under surface of the upper valve flap. This construction is thus closely similar to that shown in Figure 5 except that the reinforcement is a single 45 strip.

In the construction shown in Figure 7, a single reinforcing strip 27 is employed and the strip extends substantially the entire length of the 50 bottom of the bag, one end being folded inward along the line 28 to provide a portion 29 which may be affixed to the under surface of the upper valve flap. The end 30 of the strip 27 overlies and is affixed to the end flap 12b at the end 55 opposite to the valve, and this portion of the strip reinforces and forms a strong closure for the corner which is to be permanently closed.

In a bag provided with a reinforcing strip 20, the strip may be employed as a means for closing the valve, if desired. For this purpose, the strip is carried out beyond the edges 15 of the side flaps and affixed to the upper surface of the end 5 flap 12a. A strip thus employed both for reinforcing and closing purposes cannot, of course, be applied until after the bag has been filled.

What I claim is:

A bag having a valve in the bottom thereof and 10 adapted during filling to be suspended from a filling nozzle inserted in said valve, comprising side and end flaps formed by longitudinal parallel cuts in the wall of the bag at the bottom end, the end flaps being folded inwardly towards 15 one another so that said cuts form cut ends for the side flaps and cut parallel lateral edges for the end flaps extending inwardly in the direction of the long axis of the bottom from the cut ends of the side flaps, and lying parallel to and 20 on opposite sides of said long axis, said side flaps and the outer lateral portions of each end flap being folded inwardly towards said long axis so that the side flaps lie one upon the other with 25 their cut end edges aligned and the outer lateral portions of the end flaps are folded upon themselves, said side flaps being secured to one another but being unsecured to at least the middle portion of at least one end flap to form the valve 30 at the bottom of the bag, the in-folded, outer lateral portions of each end flap being spaced from said long axis so that the respective outer 35 ends of said in-folded portions diverge outwardly from points on said cut ends of the side flaps at opposite sides of said long axis, and a reinforcing strip secured to the outer surfaces of the side flaps, said reinforcing strip being of such width that the lateral edges thereof intersect the outwardly-diverging outer end of the in-folded side portions of the respective end flaps 40 at points on opposite sides of said long axis more than half the distance from the respective points on the cut end edges of the folded side flaps from which the outer ends of the infolded side 45 portions of the end flaps diverge to the fold lines of said side flaps, and extending, in the direction of said long axis, beyond the aligned cut end edges of the side flaps to provide an unsupported valve extension of generally trapezoidal shape, said reinforcing strip being turned back upon 50 itself along the line determined by said opposite points and forming a fold-line defining the outer edge of said trapezoidally shaped portion, said turned-back portion extending back under said side flaps.

MIKAEL VOGEL-JORGENSEN.
